UNITED STATES PATENT OFFICE.

JAMES DWYER, OF DETROIT, MICHIGAN.

HEATING-STOVE.

SPECIFICATION forming part of Letters Patent No. 272,128, dated February 13, 1883.

Application filed July 27, 1882. (No model.)

To all whom it may concern:

Be it known that I, JAMES DWYER, of Detroit, in the county of Wayne and State of Michigan, have invented new and useful Improvements in Heating-Stoves; and I do hereby declare that the following is a full, clear, and exact description thereof, reference being had to the accompanying drawings, which form a part of this specification.

10 The nature of this invention relates to certain new and useful improvements in the construction of heating-stoves; and my invention consists of vertically-projected ribs formed upon the stove-body, to which to hinge the doors and form striking-faces for the latter to rest against, with each rib constructed with an exterior lap-joint to receive an interiorly-reversed lap rabbet-joint upon the other rib, so that the ribs, when united, shall be flush and circumferentially coincident, as more fully hereinafter described.

15 The invention relates especially to that class of stoves which have a series of doors in revolution upon the stove exterior.

20 Figure 1 is a perspective of that section of a stove wherein two series of doors are employed. Fig. 2 is an enlarged perspective view of a section, showing the projected rib between two of the doors in the series. Fig. 3 is a cross-section through the joint on the line xx in Fig. 2.

25 In the accompanying drawings, which form a part of this specification, A A A represent the rings by means of which the various sec-

tions of the stove are divided and secured together, and B B are the series of doors which carry the mica lights. These are made in the usual way, so that a description thereof is unnecessary. The frames to which the doors are hinged are made in sections with overlapping ends.

30 In Fig. 3, a represents one end of one of these sections, with an exterior lap-rabbet, b , to engage with the interior lap-rabbet, c , on the adjoining end of the adjacent section, d . The members of these sections are both exteriorly rabbeted, as at $e e$, to form a striking-surface, against which the ends of the doors rest. These rabbets are of such depth that when the doors are closed there will be a flush and coincident surface presented. By this construction the vertical ribs are projected out flush with the adjoining parts, while greater strength is obtained in hinging the doors thereto.

35 What I claim as my invention, and desire to secure by Letters Patent, is—

40 In a stove having a series of doors in revolution upon its exterior, a lap-joint, between the sections of which the door-frames are constructed, the outer surface of which is circumferentially flush with the outer surface of said doors, and furnishes the means of hinging the same, substantially as and for the purposes described.

JAMES DWYER.
